UNITED STATES PATENT OFFICE.

ARTHUR L. PLIMPTON, OF BOSTON, MASSACHUSETTS.

RAILWAY-TRACK.

995,369.

Specification of Letters Patent. Patented June 13, 1911.

Application filed February 24, 1910. Serial No. 545,689.

To all whom it may concern:

Be it known that I, ARTHUR L. PLIMPTON, a citizen of the United States, residing in Boston, county of Suffolk, and State of Massachusetts, have invented an Improvement in Railway-Tracks, of which the following description, in connection with the accompanying drawings, is a specification, like letters on the drawings representing like parts.

This invention relates to a novel railway track and to a novel method of making the same.

The present invention has for its object to provide a railway track composed of rails having continuous wearing surfaces, free from breaks or joints, whereby the life of the track and of the rolling stock is materially prolonged and the cost of maintenance reduced to a minimum, while at the same time easier riding of the cars is obtained with a material lessening of noise.

As now commonly constructed and known to me, the rails of a street railway track to which this invention is particularly applicable, are composed of lengths or sections, which are abutted and secured closely together by suitable fastening devices, so that as little space as possible is left between succeeding rail sections. Experience has shown however, that when the slightest crack or space exists between the rail sections, one of the rail sections which may be termed the receiving rail section, as it receives the car wheel from the preceding section, is subjected to a slight blow by the wheel passing over the crack, which starts a slight depression or cavity in the receiving rail at the end of the same, and this depression or cavity when once started increases rapidly and in time renders the rail section unfit for further use. In the meantime, the use of the rail section is attended by an uneven running of the car and by disagreeable noise caused by the blow of the car wheel. Furthermore, the life of the track is materially shortened as the receiving rail may be only defective at the joint while the remaining portion may be in good working condition. So also, the expense of replacing a worn rail is very considerable, espe-

cially when it is laid in a paved street in which the paving blocks are bound together by tar or other binder, or in a street which is provided with an asphalt or macadam surface.

The above mentioned objections are overcome by the present invention, which is applicable to old or new tracks, and which consists in uniting the head portions of contiguous or adjacent rail sections, so as to form a plain track having a continuous tread surface free from breaks or joints while the webs of adjacent rail sections are mechanically joined in the usual manner. This result may be accomplished as will be described.

These and other features of this invention will be pointed out in the claims at the end of this specification.

Figure 1 represents in side elevation a sufficient portion of a railway track embodying this invention to enable the same to be understood. Fig. 2, a plan of the rails shown in Fig. 1. Fig. 3, a side elevation of a worn rail. Fig. 4, a side elevation of two adjacent rail sections before their tread surfaces are united, and Fig. 5, a modification to be referred to.

Referring to the drawings, *a*, *b*, represent two sections of a rail of the track of a street railway, which are abutted and secured together by joint fastenings *c* bolted together through the web of the said rails.

In accordance with this invention, a space is formed between the tread surfaces 10, 12, of the rails *a*, *b*, which may be accomplished by sawing or grinding a triangular portion from the head of each rail section at its opposite ends so as to leave preferably a V-shaped notch or opening 13 (see Fig. 4) between the tread surfaces of adjacent rail sections, the apex of which extends substantially to the web of the rails. This space is then filled with metal 15 of the same quality or character as the rail sections and is molecularly united to both, so that the tread surface 10 of one rail section *a* is united to the tread surface 12 of the next rail section *b* to form a continuous tread surface. The opening 13 may be filled with steel by melting the end of a

steel rod with the oxy-acetylene flame, which melted metal drops into the opening and molecularly unites with the walls of said opening which are also heated by said flame. In this manner the opening 13 is filled up step by step and the heads of adjacent rail sections are molecularly united so as to obtain a continuous tread surface. Any surplus metal built up above the level 10 of the tread surfaces may be ground off or otherwise removed so as to bring the upper surface of the filling metal in the same plane as the tread surface of the rail sections. This operation is repeated at the 15 joints of adjacent rail sections, until the whole or any desired part of the plain track rails have been provided with continuous and unbroken tread surfaces.

It will be understood, that the web and 20 base portions of adjacent rail sections are not required to be united, and consequently old tracks now in use and having a break in the tread surface between adjacent rail sections, may be readily converted into a practically noiseless track having continuous or 25 unbroken tread surfaces, while the base and web portions of the rail sections are or may be broken or separated.

In tracks now in use, worn joints having 30 a depression as 20, Fig. 3, and those which are not worn, have the opening 13 formed in them by sawing, grinding or otherwise removing a portion of the tread surface of both rail sections, as represented in Fig. 4, 35 and the opening 13 thus formed is filled with metal as above described. In this manner, a railway track laid in the street and in use, can be converted into a track whose rails are 40 provided with continuous or unbroken tread surfaces.

When a new track is laid, it may be unnecessary to remove a portion of the tread surfaces of adjacent rail sections, for in this case, the rail sections *a*, *b*, may be laid so as 45 to leave a space between them, the lower portion of which may be filled with a piece or section 30 of the web and base of the rail, and the space between the tread portions or heads of the rail sections *a*, *b*, may be filled 50 and molecularly united as above described, the filling piece 30 in this case being mechanically secured to the rails *a*, *b*. If desired, the new rails may have their ends at 55 their tread portions cut off in the mill after the manner represented in Fig. 4 and shipped to the railway company ready to be laid in the usual manner, and after the new track has been laid, the openings 13 may then be filled up as above described.

60 It will be seen that in both cases, that is, in old and new tracks, the rails are provided with continuous tread surfaces unbroken by joints or cracks, with the attending beneficial results above noted, while the webs and

bases of the rail sections may be separated 65 throughout the length of the track and bonded in the usual manner to obtain the desired conductivity for the current.

In practice, it is preferred to make the plain track of the railway continuous as to 70 its tread surface throughout the length of the system, but it will be understood that any portion of the plain track which is provided with a continuous tread surface of substantial length falls within this invention. 75 By the term plain track, I desire to be understood as meaning those portions of the track other than the frogs, switches and crossings.

I have herein described one method of 80 forming a continuous tread surface, but I do not desire to limit the invention in this respect. By mechanically joining the webs of adjacent rail sections as above described, the said sections, especially when composed 85 of modern heavy girder rails, are held at perfect line and surface and with such force as to withstand changes of temperature. Furthermore, new tracks can be laid in a continuous manner in a minimum time and 90 at a minimum cost, and when laid and mechanically joined, the spaces between the heads of adjacent rail sections may be filled 95 with metal to form the continuous tread surface. The mechanical joints further afford opportunity for connecting the rail sections by the usual bonds, which are of the proper capacity to carry a current which would not be properly taken care of by the head portions only of the rails. 100

Claims.

1. A railway track composed of rails having continuous and unbroken tread surfaces with their webs and bases separated at predetermined points. 105

2. The method of making a railway track composed of rails having a continuous tread surface and non-continuous webs and bases, which consists in forming a space between the heads of adjacent rail sections, mechanically joining the rail sections below the heads of the same, heating the walls of said space above the said webs and filling the space above the webs with a body of metal which is molecularly united to said walls. 110

3. The method of making a railway track composed of rails having a continuous tread surface, which consists in removing a portion of the head of adjacent rail sections to form a space, heating the head portions of adjacent rail sections, and filling the space with molten metal which is molecularly united to the heads of adjacent rail sections to form a head of a rail between the heads of adjacent rail sections which is molecularly 115 united to said adjacent heads, substantially as described.

4. The method of making a railway track

composed of rails having a continuous tread surface and non-continuous webs and bases, which consists in forming a space between adjacent rail sections, mechanically filling 5 said space for a portion of its height from the bases toward the heads of the rail sections, mechanically joining the webs of adjacent rail sections together, heating the walls of the said space above the webs, and

filling said space with metal which is molecularly united to said walls.

In testimony whereof, I have signed my name to this specification in the presence of two subscribing witnesses.

ARTHUR L. PLIMPTON.
